(57) **CLAIM**

The ornamental design for a mounting bracket, as shown and described.

DESCRIPTION

FIG. 1 is a perspective view of the mounting bracket.
FIG. 2 is an underneath view of the mounting bracket.
FIG. 3 is a top plan view of the mounting bracket.
FIG. 4 is an alternate top perspective view of the mounting bracket.

FIG. 5 is a front view of the mounting bracket; and,
FIG. 6 is a side view of the mounting bracket.
The broken lines present in the drawings are included for the
purpose of illustrating portions of the article which form no
part of the claimed design.
